FIG. 2.

Frank Newshutz Inventor

John P. Duffie Attorney

UNITED STATES PATENT OFFICE.

FRANK NEWSHUTZ, OF ALLIANCE, OHIO.

BOILER-FLUE CONNECTION.

1,294,362.

Specification of Letters Patent. Patented Feb. 11, 1919.

Application filed September 12, 1918. Serial No. 253,695.

To all whom it may concern:

Be it known that I, FRANK NEWSHUTZ, a citizen of the United States, residing at Alliance, in the county of Stark and State 5 of Ohio, have invented certain new and useful Improvements in Boiler-Flue Connections, of which the following is a specification.

This invention relates to new and useful 10 improvements in boiler flue connections for locomotives or other steam engines.

The primary objects of this invention are, first, to provide a boiler flue connection which is simple and economical in construction, second, that will last for a considerably 15 longer time than the kind now in use and third, will provide an absolutely water and steam tight joint between the ends of the flue and the flue sheet or wall and prevent 20 any water or steam from blowing into the flues.

With the foregoing and other objects in view that will appear as the nature of the invention is better understood, the same 25 consists in the novel features of construction, combination and arrangement of parts illustrated in the drawings and more particularly pointed out in the appended claims.

30 In the accompanying drawings:—

Figure 1 is a fragmentary sectional view of one end of a boiler flue and the flue wall or sheet, illustrating the application of my invention.

35 Fig. 2 is a front view of Fig. 1 and Fig. 3 a detail edge view of a brass or copper packing element used or interposed between the clamping plug and the end of the flue, at the joint.

40 Referring to the drawings for a more particular description of the invention and which drawings are for illustrative purposes only and are therefore not drawn to scale, the numeral 1 indicates the flue wall or

45 sheet and 2 the adjacent end of the flue. As shown, said end of the flue, at the joint, is considerably thickened, as at 3, and is slightly offset inwardly, leaving an annular space between the outer surface of said

50 thickened portion and the wall or edge of the flue opening 4 in which is arranged a packing ring 5 of brass, copper or other suitable material. The flue opening 4 is provided in its outer portion with an annular or circumferential recess 6, and in carrying out the invention, the outer end of

the thickened portion 3 of the flue is bent or crimped inwardly, as at 7, over the packing ring 5 against the vertical wall 8 of said recess 6.

60 A clamping ring 9, comprising a body portion 10 and an annular exteriorly threaded head or rim 11, is screwed into the recess 6 of the flue opening, the body portion of said clamping ring fitting within the thickened end portion of the flue and the inner face of the head or rim of said ring provided with an annular concave recess 12.

65 It will be observed that an annular or circumferential space 13 is left between the outer surface of the body portion of the clamping ring and the inner edge or wall of the thickened end portion of the flue to receive a packing ring or gasket 14 of brass, copper or other suitable material, the outer 70 portion of which ring or gasket 14 is adapted to fit in the concave recess 12 in the head or rim of the clamping ring and is bent or crimped inwardly, as at 15, against the in-turned flange 7 of the thickened end portion 80 of the flue.

75 It will be noted that the threaded clamping ring keeps the extreme heat off the wall of the flue at the joint; also, that the head or rim of the clamping ring keeps the water and steam from leaking into the flue and coming in contact with the fire, thus allowing the engine to steam more freely. The copper gasket forms an absolutely water and steam tight joint and prevents the water and steam from blowing into the flue, even 90 should the flue leak.

80 From the foregoing description taken in connection with the drawings, it is thought that the construction, operation and advantages of this invention will be readily understood without requiring a more extended explanation.

85 Having described my invention, what I claim as new and desire to secure by Letters Patent, is:—

1. In combination with a boiler flue wall or sheet formed with a counter bore or annular recess in the flue opening, a flue formed at one end with a thickened portion 105 extending into the flue opening and bent or crimped inwardly against the vertical wall of said counter bore, a metallic gasket encompassing the thickened inwardly bent portion of the flue and a clamping ring 110 screwing into the counter bore of the flue opening against said gasket.

2. In combination with a boiler flue wall or sheet formed with a counter bore or annular recess in the flue opening, a flue formed at one end with a thickened portion extending into the flue opening and bent or crimped inwardly against the vertical wall of said counter bore, a metallic gasket encompassing the thickened inwardly bent portion of the flue, a clamping ring screwing into the counter bore of the flue opening against said gasket and a clamping ring between the thickened offset end portion of the flue and the inner edge of the flue opening.
3. In combination with a boiler flue wall or sheet formed with a counter bore in the flue opening, a flue formed at one end with a thickened portion extending into the flue opening and bent or crimped inwardly against the vertical wall of said counter bore, said thickened portion being slightly offset inwardly, a metallic gasket encompassing the thickened inwardly bent portion

of the flue, a clamping ring screwing into the counter bore of the flue opening against said gasket and a clamping ring between the thickened offset end portion of the flue and the inner edge of the flue opening.

4. In combination with a boiler flue wall or sheet formed with a counter bore in the flue opening, a flue formed at one end with a thickened portion extending into the flue opening and bent or crimped inwardly against the vertical wall of said counter bore, a metallic gasket encompassing the thickened end portion of said flue and a clamping ring screwing into the counter bore of the flue opening and formed in the inner edge of its head or rim with an annular circumferential recess to receive the inwardly bent or crimped portion of said gasket.

In testimony whereof I affix my signature.

FRANK NEWSHUTZ.
